UNITED STATES PATENT OFFICE.

LESTER KULP, OF CHICAGO, AND ROBERT S. CORLETT, OF EVANSTON, ILLINOIS, AS
SIGNORS TO KULP THEFTPROOF LAMP COMPANY, OF CHICAGO, ILLINOIS, A COR-
PORATION OF ILLINOIS.

DEVICE FOR REMOVING THEFTPROOF LAMPS.

Application filed May 31, 1924. Serial No. 717,136.

This invention relates to devices for removing theftproof lamps from receptacles and has particular reference to such devices which may be used to remove theftproof 5 electric lamp bulbs having base members rotatable within the shell contact when the bulb is in theftproof condition within a receptacle. Theftproof lamps of this character are disclosed in the patent to Daniel R. 10 Coughlin, No. 1,437,723, issued December 5, 1922.

One of the objects of this invention comprises the provision of a combination tool for breaking, without excessive shattering, 15 the neck portion of theftproof electric lamp bulbs of the character above indicated preparatory to the removal of the bases of such bulbs from their theftproof condition in receptacles.

20 A further object of this invention is to provide means in connection with such a combination tool for collecting and retaining the broken parts of the lamp bulb when shattered. More specifically it is an 25 aim of this invention to provide a fabric sack for receiving the parts of the broken bulb, such sack having an expansible opening permitting bulbs of various dimensions to be inserted and substantially wholly enveloped by the sack in order to prevent scattering of the broken glass.

30 A further aim of this invention is to provide means on the combination tool not only for breaking the lamp but also for engaging and removing the shell contact from the 35 receptacle after the bulb is broken.

Further objects of the invention will become apparent from the following description, the appended claim and the accompanying 40 drawings.

For purposes of description and illustration several specific embodiments of the invention are shown in the accompanying drawings, in which—

45 Figure 1 is a side elevational view of an assembled device embodying the invention, showing the device in operative position ready to be used in crushing a lamp bulb;

Fig. 2 is an enlarged detail view of the device shown in Fig. 1;

Fig. 3 is a sectional view partly broken away and taken upon the line 3—3 of Fig. 2;

Fig. 4 is a perspective view illustrating

the operation of the tool for engaging and removing the shell contact from a receptacle 55 after the bulb is broken; and,

Fig. 5 is an elevational view partly broken away, illustrating a modified form of the invention in operative position ready for use in crushing a lamp bulb. 60

The principal parts of the device embodying the invention and as shown in Figs. 1 and 2, comprise a fabric sack or container 10 fastened upon a tool 11, which is made in the form of pliers. The tool 11 embodies 65 a pair of jaws 12 and 13, one of which is provided with a pointed member 14. These jaws are preferably interiorly shaped with a contour substantially to fit the neck portion of a lamp bulb. The jaws 12 and 13 are 70 preferably extended as at 15 and 16 respectively, to provide tongs or pliers for engaging and removing the shell contact from a receptacle after the bulb has been broken 75 into the fabric bag 10.

The tool 11 may be provided with handles 17 and 18 of conventional plier form which comprise integral extensions to the jaws 12 and 13, respectively. The handles 17 and 18 may be pivoted upon a screw 19 in the 80 conventional manner of plier handles.

The upper peripheral edge of the sack 10 may be hemmed over a supporting hoop or wire 20. The ends of the wire 20 may be clamped as at 21 beneath a nut 22 on the 85 pivoting screw 19. The wire 20 may also be supported on one of the plier jaws as at 23. Such a support may be effected by bending the wire around the plier jaw or by soldering. 90

In using one of the lamp bulbs of the type described in the above mentioned patent, the bulb is firmly screwed into a receptacle and upon attempts being made to remove the bulb by turning the bulb out, the lamp base 95 will freely turn within the threaded shell contact and hence the threaded shell contact cannot be screwed out. The lamp bulb is then in a theftproof condition. However, when it becomes necessary to remove the 100 lamp when worn out, such removal may be accomplished with the device embodying this invention in the following described manner. The sack or fabric bag 10 is drawn up around the lamp bulb, as shown 105 in Fig. 1, and the neck of the bulb is re-

ceived between the jaws 12 and 13. Upon applying a slight pressure to the handles 17 and 18, the pointed member 14 will puncture the glass. Immediately upon puncturing the glass, atmospheric air will of course be admitted to the bulb. Accordingly, the degree of vacuum within the bulb will be considerably reduced before the collapse of the whole neck portion takes place. For this reason the collapse will be less violent than would be the case if the glass were not first punctured before the crushing action of the jaws 12 and 13 takes place. Accordingly, the pointed member 14 not only serves to accurately locate the point at which the breaking action is to be initiated, but also serves to prevent a violent shattering of the glass. As a result, the bulbs may be broken with very little noise and all of the broken parts will drop into the bag 10. In most cases, the main part of the bulb will remain whole, only the neck portion being broken.

After the bulb has been broken as above described, the lower edge (as at 24 in Fig. 4) of the threaded shell contact may be then grasped by the jaw members 15 and 16. In order to readily accomplish this purpose the jaw members 15 and 16 are preferably extended upwardly as best shown in Fig. 3, so that the threaded shell contact may be firmly gripped and then turned out of the receptacle.

In Fig. 5 a modified form of the device is shown in which a tool 25 similar to the tool 11 is provided. However, a fabric bag 26 is here provided with an expansible opening permitting bulbs of various dimensions to be inserted into the bag. The upper periphery of the bag is hemmed over an elastic bag as at 27, which is fastened to a pivoting

screw 28 in any suitable manner as by an eyelet 29. With this form of the device, the bag may be inserted over lamps having very large bulb portions. Yet after the lamp has been inserted the elastic band will draw together the opening of the bag so that it will fit closely around the neck portion of the bulb and thus prevent shattering of the particles of glass when the lamp is crushed. 45

While several embodiments of the invention have been shown and described, it is not desired however, that any limitations be imposed thereupon except as specifically set forth in the appended claim or required by the prior art since mechanical expedients 55 or equivalents of the various elements are intended to come within the scope of the invention.

Having thus described our invention, what we claim as new and desire to secure by Letters Patent of the United States, is:

A combination tool for removing theft-proof electric lamp bulbs that have a base member which is rotatable within the shell contact when the lamp is in theft-proof condition within a receptacle, said tool comprising tongs having jaws for engaging and crushing the neck portion of the bulb, said jaws being extended to form pliers for engaging and removing the shell contact from a receptacle after the bulb is broken, and a fabric bag mounted on the tool for receiving and retaining the parts of the bulb when broken, at least one of said jaws being movable independently of said bag. 75

In witness whereof, we have hereunto subscribed our names.

LESTER KULP.
ROBERT S. CORLETT.
